UNITED STATES PATENT OFFICE.

GEORGE GRAFF, OF TOLEDO, OHIO, ASSIGNOR TO THE DURA COMPANY, OF TOLEDO,
OHIO, A CORPORATION OF DELAWARE.

DESIGN FOR A CORNER LIGHT.

Application filed December 13, 1926. Serial No. 20,040. Term of patent 14 years.

To all whom it may concern:

Be it known that I, GEORGE GRAFF, a citizen of the United States of America, residing at Toledo, in the county of Lucas and State of Ohio, have invented a certain new, original, and ornamental Design for a Corner Light, of which the following is a specification, reference being had therein to the accompanying drawings, forming part thereof, in which—

Figure 1 is a plan view of a corner light, showing my new design;

Figure 2 is a side elevation thereof.

I claim:

The ornamental design for a corner light, substantially as shown.

GEORGE GRAFF.
